(57) **CLAIM**

(**) Term: **14 Years**

The ornamental design for a device for receiving and collecting biosignals from electrodes and transmitting same, as shown and described.

(21) Appl. No.: **29/325,651**

DESCRIPTION

(22) Filed: **Oct. 3, 2008**

FIG. 1 is a perspective view of a device for receiving and collecting biosignals from electrodes and transmitting same;

(51) **LOC (9) Cl.** **10-04**

FIG. 2 is a top plan view thereof;

(52) **U.S. Cl.** **D10/81**

FIG. 3 is a front elevational view thereof;

(58) **Field of Classification Search** D10/46,

FIG. 4 is a rear elevational view thereof;

D10/78, 81; D24/186, 187, 216, 224, 232;

FIG. 5 is a left side elevational view thereof;

340/575; 348/163; 600/437, 443, 500, 502,

FIG. 6 is a right side elevational view thereof; and,

600/503, 544

FIG. 7 is a bottom plan view thereof.

See application file for complete search history.
